UNITED STATES PATENT OFFICE.

WILLIAM WILKIE, OF DENNISTOUN, GLASGOW, SCOTLAND.

PRESSING-MACHINE.

1,320,813.

Specification of Letters Patent.

Patented Nov. 4, 1919.

Application filed September 12, 1918. Serial No. 253,822.

To all whom it may concern:

Be it known that I, WILLIAM WILKIE, of 34 Garthland Drive, Dennistoun, Glasgow, Scotland, engineer, have invented certain 5 new and useful Improvements in Pressing-Machines, of which the following is a specification.

My invention, which relates to machines for pressing cloth, has for its object the 10 treatment of the various parts of wearing apparel such as collars, cuffs, seams, edges and analogous parts, a more effective method of applying pressure to the raisable block under varying degrees to suit the various 15 thicknesses of cloth, and adapting various forms and sizes of blocks necessary in the pressing operation.

The machine is of the type wherein two longitudinal heated blocks are used, one superimposed above the other and the lower one capable of being raised and lowered. According to my present invention, the upper one is not raisable but slideable at will 20 along guide rail and made to sustain pressure at any position along said rail, while the lower block is rendered adjustable for 25 pressing any thickness of material which is interposed between said two blocks. The said lower block is provided with two plun- 30 gers which are connected thereto from the underside. The lower end of the plungers bears upon the surfaces of a pair of levers now to be referred to. These plungers are elevated or raised by the depression of a 35 foot pedal, pulling down the members of compound levers connected to said pedal; said levers are jointed at nearly right angles and fulcrumed or pivoted at or near their extremities upon a transverse shaft. The 40 free ends or extremities of said levers support the ends of the plungers with a bar, having inclined planes formed thereupon, interposed therebetween, and exert upon them the maximum lever action. It should 45 be explained that the bar is adjustable slidably as opposed to known means of adjusting a wedge by a screw device. The foot pedal is capable of being drawn out or extended. A guard or receptacle of trough 50 formation may be used to receive the articles under treatment and keep them from being soiled.

In order that my invention may be properly understood and readily carried into ef-

fect, I have hereunto appended one sheet of 55 drawings, of which—

Figure 1 is an elevation of a machine for pressing cloth and embodying my invention.

Fig. 2 is an end view of the same broken away at its lower end to show the lever ar- 60 rangement.

Fig. 3 is a horizontal section taken on the line *a*, *b*, Fig. 1, and

Fig. 4 is a part plan of one form of one 65 of the blocks, all hereafter more fully referred to and described.

Referring to the drawings, *A* is the framework, *B* is the upper block slideable horizontally by the handle *C* along the guide rail *D* and made to sustain pressure at any position along said guide rail. *E* is the lower block capable of being raised and lowered and on which the articles to be treated are placed and rendered adjustable for pressing any thickness of material. *F*, *G*, are the two 70 plungers screwed or otherwise secured to the underside of the lower block *E*. A pair of levers *H*, *I*, are fulcrumed on a cross bar *L* and bear at their front ends under the bar *P* as at *H*² and *I*². Links *H*¹, *I*¹ have their 75 upper ends pivotally jointed to the rear ends of said levers as at *J*, *K*. The lower ends of the links *H*¹ and *I*¹ are connected to the pedal *N* whose rear end bears and is fulcrumed on the transverse bar *O*. Interposed 80 between the ends of the plungers *F* and *G* aforesaid and the extremities *H*², *I*² of levers *H* and *I*, is a bar *P*. This bar has inclined planes *P*¹, *P*² which slide more or less under the ends of the plungers *F* and *G* when it is 85 required to adjust the space between upper and lower blocks by means of a lever *Q* which is fulcrumed as at *Q*². The outer end of this lever forms a handle *R* and the inner end thereof is connected pivotally as at *Q*¹ to 90 a link *O*³. Said link is pivotally connected as at *O*² to the bar *P*.

It will be seen that the depression of the 95 pedal *N* will depress the lever *H*¹ and raise the free ends *H*² and *I*² of the levers *H* and *I*, and this movement in coaction with the plungers *F*, *G*, brings the block *E* into pressing contiguity with the upper block *B*. A weight or counterpoise *S* having a lever *S*¹ connected to the pedal and fulcrumed at *S*² 100 to the frame of machine, is employed to raise the pedal immediately after depression. *T* are hollow guards or receptacles to keep the 105

articles from the machine or floor. Said guards or receptacles are indicated in dotted lines in Fig. 3 and are arranged on opposite sides of that portion of the frame A on which the block E is mounted. The block shown in Fig. 4 constitutes one of a variety of forms which may be used to meet the pressing requirements. The pedal includes a slideable member N¹ which enables the 10 pedal to be lengthened or shortened to vary the leverage thereof. Said slideable member passes through a stirrup N which is connected to the lever S¹, said member N¹ also having on its under side a series of rack 15 teeth T¹ any one of which may be engaged with the lower side of the stirrup to secure said member N¹ at any desired adjustment.

Claim:

In a machine or the type set forth, an upper block slideable horizontally and longitudinally in relationship to a lower adjustable 20

block adapted to be raised and lowered and exert pressure on the under surface of said upper block, a pair of plungers depending from and connected to the underside of said 25 lower block, a pair of levers fulcrumed on a single transverse horizontal bar carried in the framework of the machine and acted upon by a foot pedal, a bar interposed between the lower ends of plungers and the 30 free ends of the aforesaid pair of levers having inclined planes formed on the upper side and capable of sliding more or less underneath said plungers by lever mechanism, and means to return the pedal to normal 35 position after depression.

In testimony whereof I affix my signature in the presence of two witnesses.

WILLIAM WILKIE.
